(57) **CLAIM**

The ornamental design for a multifunctional bag, as shown and described.

DESCRIPTION

FIG. 1 is a perspective view showing of a multifunctional bag showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front elevational view of the bag element of the multifunctional bag shown in FIG. 1;

FIG. 9 is a rear elevational view thereof;

FIG. 10 is a left side elevational view thereof;

FIG. 11 is a right side elevational view thereof;

FIG. 12 is a top plan view thereof;

FIG. 13 is a bottom plan view thereof;

FIG. 14 is a front elevational view of the strap element of the multifunctional bag shown in FIG. 1, and a rear elevational view thereof is a mirror image of the front elevational view of the strap element of the multifunctional bag; and,

FIG. 15 is a perspective view showing of a multifunctional bag shown in FIG. 1 in an open state.

The waved lines shown in the center of the strap element in FIG. 14 depict a symbolic break. Any portions within the symbolic break form no part of the claimed design.

1 Claim, 12 Drawing Sheets
